United States Patent Office

Des. 227,065

Patented June 5, 1973

227,065

BOOKRACK

Edward M. Mayers, Hong Kong, assignor to Action-Lobeco, Imports, Ltd., Cheswick, Pa.

Filed May 24, 1971, Ser. No. 146,580

Term of patent 14 years

Int. Cl. D6—04

U.S. Cl. D6—184

FIG. 1.

FIG. 2.

FIG. 3.

FIG. 1 is a side perspective view of a bookrack of the invention; the sides away from the sides shown being identical in appearance to the sides shown in the drawing;

FIG. 2 is a plan view of the bookrack embodiment of FIG. 1; and

FIG. 3 is a side perspective view of another embodiment of the bookrack of the invention; the sides away from the sides shown being identical in appearance to the sides shown in the drawing, and the plan appearance being the same as seen in FIG. 2.

I claim:

The ornamental design for a bookrack, as shown.
